A. ALDRICH

ROLL

Filed Oct. 18, 1922

Witness:

Ed. Johnson

Inventor:
Alonzo Aldrich
By *A. Alonzo Aldrich, Atty.*

UNITED STATES PATENT OFFICE.

ALONZO ALDRICH, OF BELOIT, WISCONSIN.

ROLL.

Application filed October 18, 1922. Serial No. 595,256.

To all whom it may concern:

Be it known that I, ALONZO ALDRICH, a citizen of the United States, residing at Beloit, in the county of Rock and State of Wisconsin, have invented a certain new and useful Improvement in Rolls, of which the following is a full, clear, concise, and exact description, reference being had to the accompanying drawings, forming a part of this specification.

My invention relates to rolls, and particularly to a construction of roll especially adapted for use in paper making machines.

The object of the invention is to provide a roll which will be both light and durable.

In carrying out the invention I provide a roll whose body portion is composed largely or entirely of aluminum, and is therefore very light in weight. Outside of the aluminum body I provide a shell or covering of other material, preferably copper or brass or rubber. This latter adds greatly to the durability of the roll, preventing deterioration of various kinds which often occurs in aluminum.

In the accompanying drawings Fig. 1 is a side view of a portion of a paper making machine provided with table rolls embodying my present invention;

Fig. 2 is a longitudinal view of one of said table rolls on an enlarged scale, part of the same being broken away for convenience of illustration;

Fig. 3 is a cross section taken on line 3—3 in Fig. 2;

Fig. 4 is a view similar to Fig. 3 of a modified form of construction.

Referring to the drawings and first to Figs. 1, 2, and 3, I show a paper making machine of the Fourdrinier variety having a table 1 with a breast roll 2 and table rolls 3—3, over which passes a wire 4. The rolls 3 are preferably constructed as shown in Figs. 2 and 3, in which 5 is a cylinder made of light metal, preferably aluminum, and 6 is a shell or covering over the same made of a different material preferably copper, brass or rubber, or the like. Such a roll will be very light because of the aluminum body, but will also be very durable, much more durable than aluminum alone, because deterioration of the aluminum is prevented by the shell or covering 6, it being known that in paper making machines, for example, aluminum rolls will be unfavorably affected

by the paper pulp carried by the wire, the chemical in the water being perhaps the chief cause of aluminum deterioration.

The outer covering or shell 6, as shown in Fig. 3, is constructed separately and applied mechanically to the inner body portion 5. In Fig. 4, however, the outer covering or shell 6^a is shown applied to the body 5 by means of electrolytic action.

It will be understood that changes and modifications may be made without departing from the spirit of the invention, and further that although the improved rolls are herein shown in connection with a paper making machine, they can be advantageously used for other purposes.

What I claim is:

1. A roll having its body portion made of metal of light weight and provided with a protective covering of a different and more durable material.

2. A roll having its body portion made of aluminum and provided with a protective covering.

3. A paper making machine having rolls for the wire having their body portions made of aluminum and their exterior cylindrical surfaces made of a material not unfavorably affected by paper pulp.

4. A roll having its body portion made of metal of light weight and provided with a protective covering of a different material.

5. A roll having its body portion made of aluminum and provided with a protective covering of brass.

6. A roll having its body made of aluminum material and provided with a protective covering of a copper metal.

7. A roll embodying aluminum in its construction for purposes of lightness and also embodying other material arranged in a protective manner for protecting the aluminum against unfavorable action by the paper pulp.

8. A roll embodying aluminum in its construction for the purpose of lightness and also embodying copper metal arranged in a protective manner for protecting the aluminum against unfavorable action by the paper pulp.

In witness whereof I hereunto subscribe my name this 22nd day of September, A. D., 1922.

ALONZO ALDRICH.
